UNITED STATES PATENT OFFICE.

ALBERT ABERG, OF PODGORA, AUSTRIA-HUNGARY.

MACHINE FOR CATCHING SPLINTERS, &c.

SPECIFICATION forming part of Letters Patent No. 691,344, dated January 21, 1902.

Application filed September 29, 1899. Serial No. 732,108. (No model.)

To all whom it may concern:

Be it known that I, ALBERT ABERG, a subject of the King of Sweden and Norway, residing at Podgora, Görz, Austria-Hungary, have invented certain new and useful Improvements in or Relating to Machines for Catching Splinters or other Small Fragments of Material, (for which I have made application for Letters Patent in Austria on the 7th 5 of March, 1899, and in Germany on the 7th 10 of March, 1899,) of which the following is a specification.

The present invention relates to apparatus for use in purifying or removing impurities 15 from paper or like pulp, and comprises a vessel or trough into which the pulp is introduced and a rotating sieve-drum mounted longitudinally in said trough.

The invention particularly relates to the 20 construction of the blades in said sieve-drum whereby important advantages are obtained.

According to this invention the perforated drum is provided with a series of bent plates or blades connected at their sides or edges to 25 the central axle or hub and to the inner surface of the drum, respectively, for the purpose of drawing or sucking the pulp from the trough into the drum.

Hitherto in drums or cylinders having short 30 blades or paddles attached to the inner wall of the rotary drum the sucking effect of each blade began at the moment its edge left the level of the pulp in the trough, the pulp thus sucked in running along the inner wall of the 35 drum to the next blade and thence downward, where it accumulated until it reached the height of the outlet-openings at each end of the drum, whence it flowed out. In this way the following disadvantages were manifest: 40 First, the accumulation of pulp reaching up to the cylinder-outlets greatly interferes with the rotatory movement of the cylinder—i. e., requires an excess of driving power to overcome this effect; secondly, the pulp inside the 45 cylinders is continually being whipped about by the paddles, owing to the rapid rotation of the cylinder, whereby the suction-power of the paddles is greatly reduced. These drawbacks are fully remedied by causing the pulp 50 sucked in to flow off, this effect being obtained by continuing the blades, as in the case of turbine blades, to the central shaft.

The result is that the pulp sucked in from the trough is carried to the discharge-outlets at the cylinder ends by the continuations of the 55 blades serving as conveyer-blades, whereby the accumulation of pulp in the lowest parts of the cylinder is effectually prevented.

In the accompanying drawings, Figure 1 represents a cross-section of a pulp-strainer so 60 arranged, and Figs. 2 and 3 constructive modifications of the blades used in such apparatus. Fig. 4 shows a sectional view of a complete blade in modified form.

The trough *t* is intended to hold the pulp to 65 be treated, and in it is suitably arranged a straining-cylinder *c*, rotating with its shaft *h*. The pulp drawn in from the trough *t* by the blades *a* of the rotating cylinder *c* is discharged through an outlet *h* at one end. The 70 construction in the manner of turbine paddles of such combined suction and conveying blades has proved of great advantage whenever tested in practical trials. A falling back of the pulp drawn into the lowest 75 part of the cylinder is prevented, since any portion of the pulp driven against the inner periphery of the sieve-surface and inclined to adhere there is swept off by other portions striking against it and carried away by the inner parts of the blades serving as conveyers. 80

In order to prevent a stopping up or clogging of the openings in the sieve-cylinder *c* in the course of the very rapid discharge at the outlet *h* of the pulp drawn in, the inner 85 side of the cylinders is kept and swept clear, owing to the special construction of the blades as represented in the accompanying drawings. These blades are provided with nose-shaped projections *n*, extending in the 90 direction of their length, which are intended, owing to the resistance they offer by reason of the acting face of the projection being practically perpendicular to the inner face of the curved wall of the cylinder *c*, to agitate part of the pulp drawn in, thereby constantly effecting the sweeping clear of the inner side of the cylinder, as described above. The blades extending from end to end may also be provided with perforations, as seen 95 in Figs. 2, 3, and 4. In Fig. 2 I show a blade provided with a perforation *o*, while in Fig. 3 I show a blade provided with a perforation *o* and projection *i*, partly overlapping the per-

foration *o*. In Fig. 4 is more clearly shown the arrangement of the perforation *o* and projection *i* relatively to the nose-shaped projection *n*. In this construction that part of the 5 blade from the shaft to the orifice will act as a conveyer and the part from the orifice to the periphery of the cylinder as a suction-blade. The projections *i* serve the same purpose as the nozzle-shaped projections *n* and 10 at the same time prevent the material from passing to any great extent through the openings *o*, which are provided for the sole purpose of affording the air drawn in at the same time the opportunity of escaping into the next 15 chamber, and thus obviate the pounding which would be caused by the compression of air and pulp in the interior of the cylinder.

What I claim as my invention, and desire to secure by Letters Patent, is—

20 1. Paper and like pulp purifying apparatus, comprising a rotatory straining-cylinder provided with bent blades extending from the inner surface of the cylinder to the central shaft, said blades being provided with 25 nose-shaped projections *n* extending from

end to end of the blades, substantially as set forth.

2. In apparatus of the kind described, a rotatory straining-cylinder, a series of bent blades extending from the central shaft of said cylinder to the inner surface thereof, and provided with nose-shaped projections extending from end to end of the blades, and also having orifices, substantially as described. 30

3. In apparatus of the kind described, a rotatory straining-cylinder, a series of bent blades extending from the central shaft of said cylinder to the inner surface thereof, and provided with nose-shaped projections extending from end to end of the blades and orifices 40 in said blades, and projections over said orifices, substantially as described.

In testimony whereof I have signed my name to this specification in the presence of two subscribing witnesses.

ALBERT ABERG.
